UNITED STATES PATENT OFFICE.

CHARLES F. PYM, OF WINDSOR, ONTARIO, CANADA, ASSIGNOR OF ONE-HALF TO KRENTLER BROTHERS COMPANY, OF DETROIT, MICHIGAN. A CORPORATION OF MICHIGAN.

TACK-MACHINE FOR OPERATING ON LASTED SHOES.

No. 892,888.

Specification of Letters Patent.

Patented July 7, 1908.

Application filed February 20, 1905. Serial No. 246,586.

To all whom it may concern:

Be it known that I, CHARLES F. PYM, a subject of Canada, residing at Windsor, in the county of Essex and Province of Ontario, Canada, have invented a Tack-Machine for Operating on Lasted Shoes, of which the following description, in connection with the accompanying drawings, is a specification, like letters on the drawings representing like parts.

Shoes are manufactured nowadays almost entirely by machinery, but there are still a few steps in their manufacture which are accomplished by hand, and one of these is the step which follows the lasting of the shoe and precedes the inseaming thereof or sewing the upper to the innersole, when the lasting tacks have to be removed and stay tacks or anchor tacks driven at the critical points determined by the skill of the operator as he removes said stay tacks. After the innersole or insole has been tacked in place on the bottom of the last, usually by three insole tacks along its center, and the upper applied, the edges of the upper about the sole are pulled by nippers over the edges of the innersole and secured in their strained position by a series of more or less closely driven lasting tacks (and usually by a tightly drawn wire about the toe), which remain until the green leather of the upper has had time to set or become fixed in position somewhat, and then a skilled operator removes by a hand tool said lasting tacks and toe wire (which would interfere with the needle in sewing the upper to the innersole), and, during said removal, whenever he sees that the stretched leather is liable to recover itself or change its position he quickly drives a stay tack to prevent any distortion or displacement, said stay tacks being driven also at other critical points according to the operator's judgment and experience, to maintain the upper in lasted position while being subsequently sewed.

In using my machine the operator simply presents the shoe to the machine, which instantly removes the lasting tacks and wire, driving a stay tack instantly at the will of the operator in whatever place desired, so that the complete result is accomplished in a superior manner and the shoe is ready for sewing in a fraction of the time heretofore required.

The constructional details of the preferred embodiment of my invention, and the opera-

tion and further advantages thereof will be pointed out more fully in the following description, reference being had to the accompanying drawings, and the invention will be further defined in the appended claims.

60

In the drawings, Figure 1 shows, in side elevation, the complete machine, illustrating the manner of operating the same; Fig. 2 is an enlarged side elevation of the head thereof; Fig. 3 is a top plan view; Fig. 4 is an enlarged perspective view showing a lasted shoe under treatment; Fig. 5 shows the head of the machine in front elevation, Fig. 6 is a sectional view on the line 6—6, Fig. 3; Fig. 7 is a detail in side elevation of one form of claw or tack remover; Fig. 8 is a fragmentary sectional view on the dotted line 8—8, Fig. 2; Fig. 9 is a longitudinal sectional view through the clutch end of the main shaft and adjacent parts; and Figs. 10 and 11 are sectional details of the clutch.

On a suitable pedestal A is mounted the head A' of the machine, whose mechanism is driven by a belt-pulley 1 mounted loosely on a shaft 2 supported in bearings 3 in the upper ends of brackets 4 on a table 5. Fast on the pulley 1 is a gear 6 in mesh with a pinion 7 for constantly rotating a shaft 8 also supported in offset bearing portions of the brackets 4 parallel and adjacent to the shaft 2. Fast on this shaft 8 is an eccentric 9 whose strap 10 carries an arm 11 pivoted at 12 to links 13, for giving a four-motion orbital movement or forward-and-backward, up-and-down motion to a tack-removing claw 14 carried by the outer end of said arm for removing the tacks. The links 13 are pivoted at 15 to a webb or main bracket 16 on the table 5.

Coöperating with the tack-remover is a rest 17 whose lower end 18 is adapted to engage with the shoe for properly positioning the latter and aiding in maintaining said shoe steady while being operated upon. This rest 17 is herein shown as slidably mounted in ways 19 for a purpose presently to be described, and adapted to be operated by a lever 20 pivoted at 21 and engaged at one end by a stud 22 of said rest, and at the other end by a rod 23 connected to a treadle lever 24 and normally held downward by a spring 25. Close to said tack-remover I provide a tack-driver for driving the stay tacks or anchor tacks, said driver being herein shown as just out of the path of movement of the claw 14 to the right facing the machine, see

115

also Fig. 8. As any usual or preferred kind of tack-driver may be employed (and the same is equally true of the tack-remover, except when otherwise specified in certain of the claims hereinafter) I have shown in the drawings merely sufficient details of a well-known mechanism to enable my present invention to be fully understood and I have omitted to show, and will therefore not describe, the internal mechanism of the tack-driver. Suffice it to say that a hammer-rod 26 is carried at the lower end of a reciprocating plunger 27 and operates in a stationary nozzle 29 which also acts as an auxiliary rest to support the edge of the shoe S or upper thereof, said plunger 27 being engaged by the forward end 30 of a bent lever 31, pivoted at 32 and carrying a roll 33 at its rear lower end. The forward end of this lever 31 is normally held downward by a strong spring 34, and is raised in opposition thereto by a cam 35 so that a tack is instantly driven every time the roll 33 escapes from the shouldered end 36 of said cam. The tacks are positioned for driving, by a reciprocating bar 37 of well known construction operated by an eccentric 38 on the shaft 2, being fed thereto from a hopper or magazine down a raceway 40 by a slide 41, lever 42 and arm 43 in connection with a distributor 44 actuated by a broken shaft 45, 46, provided with a worm-wheel 47 engaged with a worm 48 on the shaft 8 before mentioned.

As will be understood from the description thus far, the tack-remover is constantly reciprocated at a relatively high speed imparted by the gears 6, 7, whereas, as previously stated, the tack driving means must at all times be subject to the direct control of the operator, inasmuch as it is usually not necessary to drive more than four or five stay tacks for an entire shoe which may have required forty or more lasting tacks. Accordingly I provide means for intermittently rotating the shaft 2, herein shown as a clutch 49 which is brought into action by a treadle-lever 50 connected by a rod 51, normally held upward by a spring 52, to a dog 53 pivoted in a bracket 54 to engage and disengage said clutch.

Any kind of a clutch may be employed. For convenience I have herein shown the same as consisting of a flanged sleeve 55 having a recess 56 carrying a roll 57 partly occupying a wedge-shaped recess 58 in the shaft 2, the latter also having a finger 59 engaged by a spring 60 in a recess 61 of said sleeve. Said spring 60 is normally compressed, so that when the dog 53 is suddenly released from engagement with an ear 54 projecting from the flange of said sleeve 55, said spring gives a slight rotary movement to said sleeve, sufficient to carry the roll 57 into wedging engagement between the shallow portion of the shaft-recess 58 and the inner surface of the driving pulley 1, as is clearly

shown in Figs. 10 and 11, thereby causing said pulley to impart to the shaft 2 instant rotary movement. Thereupon, the cam 35 is rotated over to the right in the direction of the arrow Fig. 2, raising the arm 31 of the tack-driving mechanism which instantly drops upon passing the shoulder 36 of said cam. Just as this movement takes place, a cam-shaped member 62 wedges tightly against a friction block 63, mounted on a heavy spring-arm 64 adjustably supported on the table 5, with the result that the rotation of the shaft 2 is quickly brought almost to a stand-still, being stopped by the engagement of the ear 54 with the dog 53 which meanwhile has been brought into position therefor by the spring 52. The block 63 is provided with a notch 65 which cooperates with the cam-member 62 to prevent backward rotation of said shaft.

Thus it will be seen that when a shoe is to be operated upon, the operator simply holds the same in the general position shown in Fig. 1, with the rest 17 against the inner portion of the insole, whereupon the rapidly operating tack-puller removes the lasting tacks as rapidly as the shoe can be moved along longitudinally in front of the same, and, whenever the operator's judgment or eye calls for a stay tack, he simply depresses the treadle 50, whereupon a stay tack is instantly driven. In the present embodiment of my invention, the stay tack will be driven just outside of the lasting tack line, although it may be otherwise located if desired, or the position of the stay tack can be readily changed simply by shifting the shoe slightly as the stay tack is about to be driven. Ordinarily the stay tacks are not driven deeply, the operator controlling this in any suitable manner, for instance either by depressing the shoe momentarily by hand or by the rest 17 away from the nozzle 29. This brings me to a further explanation of the purpose and operation of the movable rest 17 taken in connection with certain features of the tack-remover not yet explained. Viewing Fig. 4 it will be noted that the different tacks are shown as inserted in the shoe to different depths, the stay tacks t being only slightly inserted, as already stated, and most of the lasting tacks t' being left projecting some distance excepting adjacent the heel, as indicated at t'' where they are usually driven down further, while the insole-tacks t^3 are driven hard down, the middle one as shown in said Fig. 4 being indicated as having the head actually embedded in the relatively spongy insole. Also occasionally a lasting tack gets driven inside of the usual stitch-receiving lip m . To enable my machine, therefore, to perform all the operations of every kind in connection with the tacks, wherever and however they may be placed in the

bottom of a lasted shoe, I have not only made the tack puller or claw angularly adjustable, as indicated at 66, Fig. 7, but I have provided it with a bent end 67; preferably slightly upturned or scoop-shaped at its forward end 68 as best shown in Fig. 4, although for certain purposes it may be deflected straight down, as indicated at 69, Fig. 7. And by having the rest 17 adjustable and under the direct control of the operator, it will be seen that the shoe may be instantly brought to the exact position required for removing any individual tack irrespective of the awkward position it may be in. For instance, if the central tack ⁷³ is to be removed, the operator raises the rest 17 so as to bring the middle of the innersole in direct line with the end 68 of the claw, thereby permitting the latter to dig under the embedded head of the tack, or, if the toe wire is to be removed, the operator gives a quick, downward movement to the rest 17 in conjunction with the forward movement of the claw. In other words by ²⁵ having the claw angularly shaped, as shown, it is capable of digging downwardly for removing embedded or bent tacks, even tacks which may be inside of the lip as above mentioned, and by having the vertical position of the rest 17 controlled at will, the shoe may be instantly brought by the operator to the most advantageous position for extracting or for driving any tacks desired. By providing a foot-operated rest to ³⁵ resist the upward pressure of the hand-manipulated shoe when presented to the rapidly and constantly moving tack-puller and intermittently-operated tack-driver, I have found that extreme accuracy and rapidity of results can be secured. A further advantage of the manually-regulated or adjusted rest or work-guide, is that the operator can thereby readily accommodate the machine to different thicknesses of ⁴⁰ upper. That is to say, if the upper is very thick, the rest must be depressed, in order to engage the lower plane of the insole, for normal operation, whereas if a very thin upper, it will more nearly coincide with the ⁴⁵ plane of the insole and, therefore, the rest need not be materially depressed therefor. It is desirable to change the angle of the claw 14 to suit different classes of work and kinds of leather.

⁵⁰ I have already sufficiently set forth the operation of my machine in the course of the description thereof. Briefly stated, the operator presents one end of the shoe to the machine with the innersole against the end ⁵⁵ 18 of the rest, and then quickly moves the shoe longitudinally along, while the reciprocating tack-puller, with its four-motion movement, quickly draws all the tacks in its path, and, as he sees the need of a stay tack, ⁶⁰ he instantly drives one by depressing the le-

ver 50 and passes right along to drawing adjacent lasting tacks. In Fig. 4 I have indicated two stay tacks as having been driven, and have indicated by dotted lines the position previously occupied by the intervening ⁷⁰ lasting tacks. Whenever the operator finds a tack driven in further than the others, or not as far as the others, he raises the rest or else lowers it, as the case may be, so as to change the plane of the shoe or the angle at ⁷⁵ which it is presented to the claw-end 68 for enabling the latter properly to engage the head of the tack, whether the latter be deep down or standing high with relation to the leather.

Not only is the work accomplished by my machine much more quickly and evenly or more satisfactorily, but a comparatively unskilled workman can operate it, as it does not require the expertness and skill called for by ⁸⁰ the hand work, and it leaves the workman entirely free to direct all his attention to his work without being inconvenienced and lacerated by a quantity of stay tacks carried in the mouth as has heretofore been the custom ⁸⁵ of these workmen.

As already intimated, I wish it understood that I do not intend to limit my invention to the constructional details herein presented, excepting as stated in the claims.

Having described my invention, what I claim as new, and desire to secure by Letters Patent of the United States, is:

1. The combination, in a machine for operating on lasted shoes, of a work rest, to be engaged by the shoe, means under the control of the operator for varying the position of the work rest, tack-removing means, and means operable at will for driving a tack.

2. The combination, in a machine for operating on lasted shoes, of a work rest to be engaged by the shoe, means under the control of the operator for varying the vertical position of the work rest, and means operable at will for driving a tack.

3. The combination, in a machine for operating on lasted shoes, of tack-moving means, a work rest constructed and located to engage the bottom of the lasted shoe at such a distance as to bring the line of lasting tacks between the engaging end of the work rest and the tack-moving means, and to permit the instant free movement of the shoe laterally in any direction, and means under the control of the operator for varying the vertical position of the work rest to cause the tack-moving means to engage the shoe at different angles or directions according to the exigencies of the work.

4. The combination, in a machine for operating on lasted shoes, of a tack-moving device, means for giving said device a forward horizontal movement terminating in a short upward movement for vertically moving the tacks, a work rest constructed and located to

engage the bottom of the lasted shoe at such a distance as to bring the line of lasting tacks between the engaging end of the work rest and said tack-moving device, and to permit 5 the instant free movement of the shoe laterally in any direction, and means under the control of the operator for varying the vertical position of the work rest to cause the tack-moving device to engage the shoe at different angles or directions according to the exigencies of the work.

5. The combination, in a machine for operating on lasted shoes, of a tack-moving device having a tack-engaging claw whose forward end is bent angularly downward with 15 relation to the direction of forward movement of said device, means for giving said device a forward horizontal movement terminating in a short upward movement for vertically moving the tacks, a work rest constructed and located to engage the bottom of the lasted shoe at such a distance as to bring the line of lasting tacks between the engaging end of said work rest and said tack-moving 20 device, and to permit the instant free movement of the shoe laterally in any direction, and means under the control of the operator for varying the vertical position of the work rest to cause the tack-moving device to engage the shoe at different angles or directions according to the exigencies of the work.

6. The combination, in a machine for operating on lasted shoes, of a tack-moving device having a tack-engaging claw whose forward end is bent obliquely downward and curved forward at its extremity into a scoop-shaped end, means for giving said device a forward horizontal movement terminating in a short upward movement for vertically moving the tacks, a work rest constructed and located to engage the bottom of the lasted shoe at such a distance as to bring the line of lasting tacks between the engaging end of the work rest and said tack-moving device, and to permit the instant free movement of the shoe laterally in any direction, and means under the control of the operator for varying the vertical position of the work rest to cause the tack-moving device to engage the shoe at different angles or directions according to the exigencies of the work.

7. The combination, in a machine for operating on lasted shoes, of a tack-moving device having a tack-engaging claw whose forward end is bent obliquely downward and curved forward at its extremity into a scoop-shaped end, means for giving said device a forward horizontal movement terminating in a short upward movement for vertically moving the tacks, a work rest constructed and located in longitudinal alinement with

said tack-moving device in front of said claw to engage the bottom of the lasted shoe at such a distance as to bring the line of lasting tacks between the engaging end of the work rest and said tack-moving device, and to permit the instant free movement of the shoe laterally in any direction, and means under the control of the operator for varying the vertical position of the work rest to cause the tack-moving device to engage the shoe at different angles or directions according to the exigencies of the work.

8. A machine for operating on lasted shoes, including means for moving the lasting tacks, 75 consisting of a reciprocating arm, means for giving the arm an orbital moving movement, a claw in the forward end of said arm, means for adjusting the inclination of said claw angularly with reference to the longitudinal direction of said arm, a work rest for engaging the bottom of the shoe while being operated upon by said moving means, and means under the control of the operator for varying the vertical position of the work rest.

9. A machine for operating on lasted shoes, comprising a tack-mover, means for giving the same a forward and upward movement for moving tacks from the shoe, a work rest for engaging and positioning the shoe, and means for changing at will the relative normal position of said tack-mover and work rest to cause the tack-mover to engage the shoe at different angles or directions according to the peculiarities of the tacks.

10. A machine for operating on lasted shoes, comprising means for removing tacks from the shoe, mechanism for continuously operating said tack-remover, a tack-driver, means connected with the aforesaid mechanism for operating said tack-driver, said means including a clutch, and manual means for controlling said clutch, and means for frictionally stopping said operating means after the driving of each tack.

11. A machine for operating on lasted shoes, including means for moving the lasting tacks, consisting of a reciprocating arm, a claw in the forward end of said arm having its tack-engaging end bent obliquely downward at an angle to the longitudinal direction of said arm and thence slightly upturned with a scoop-shape at its extremity, and operating means therefor.

In testimony whereof, I have signed my name to this specification, in the presence of two subscribing witnesses.

CHARLES F. PYM.
